SPRAY TYPE OIL BURNER

Robert R. Witherell and Bryan Wright, Bloomington, Ill., assignors to Eureka Williams Corporation, Bloomington, Ill., a corporation of Michigan

Application March 31, 1949, Serial No. 84,675

17 Claims. (Cl. 158—76)

1

This invention relates to oil burners and has particular reference to certain new and useful improvements relating to oil burners of the low pressure type wherein oil and air are fed under a relatively low pressure to an oil and air mixing nozzle which discharges the mixture in the form of a fog into a secondary air stream, although the invention is not limited to so-called low pressure type oil burners.

Principal objects of the invention are to provide:

A novel and improved oil burner;

A novel and improved fuel supplying arrangement for oil burners;

A new and improved arrangement for supplying oil to the nozzle of a burner and for preventing the supplying of oil to the nozzle when the motor speed is below a desired minimum; and

A new and improved cutoff valve arrangement for oil burners.

Other and further objects of the invention will be apparent from the following description and claims and will be understood by reference to the accompanying drawings, of which there are five sheets, which, by way of illustration, show preferred embodiments and the principles thereof and what we now consider to be the best mode in which we have contemplated applying those principles. Other embodiments of the invention embodying the same or equivalent principles may be used and structural changes may be made as desired by those skilled in the art without departing from the present invention and the purview of the appended claims. We also contemplate that of the several different features of our invention, certain ones thereof may be advantageously employed in some applications separate and apart from the remainder of the features.

In the drawings:

Fig. 1 is an elevational view, with certain parts shown in section, of an oil burner embodying the invention;

Figs. 2 and 3 are schematic views illustrating the oil and air feeding and mixing system, Fig. 3 being a continuation of Fig. 2;

Fig. 4 is a sectional view taken along the line 4—4 of Fig. 1;

Fig. 5 is a sectional view taken along the line 5—5 of Fig. 1;

Fig. 6 is a sectional view taken along the line 6—6 of Fig. 1 and showing the driving connection between the driving shaft and the metering pump and the pressure regulating valve;

Fig. 7 is a section taken along the line 7—7 of Fig. 1;

2

Fig. 8 is a section taken along the line 8—8 of Fig. 1;

Fig. 9 is a section taken along the line 9—9 of Fig. 1 and showing the air pump;

Fig. 10 is a section taken along the line 10—10 of Fig. 1 and showing parts of the pressure regulating valve;

Fig. 11 is a sectional view taken along the line 11—11 of Fig. 1, showing certain details of the oil metering pump; and

Fig. 12 is a schematic view similar to Fig. 2 and showing a modified form of the invention.

As illustrated in Figs. 1, 2 and 3, an oil burner embodying the invention comprises in general an

air and liquid fuel pumping unit indicated generally at 20 which is constructed and arranged to supply oil and air to an air and oil mixing nozzle indicated generally at 22. The nozzle 22 is arranged to discharge a mixture of oil and air into a stream of secondary air which flows through the tube or pipe 24, such secondary air being supplied by a blower wheel or fan indicated generally at 26. An electric motor 30 is mounted on the scroll or case 32 for the fan 26 and the fan 26 is mounted on the shaft 28 of the motor.

The oil and air pumping unit 20 is mounted on the fan case 32 on the side opposite the motor 30, and the driving shaft 34 of the pumping unit 20 is connected by flexible coupling 36 to the end of the shaft 28 so that the operating parts of the pumping unit 20 will be driven with the fan 26.

The tube 24 projects forwardly from the lower part of the castings 38 and 40 which define the chamber 42 in which the blower wheel 26 is operatively arranged, such castings extending below the chamber and serving to conduct the air discharged by the blower wheel downwardly into the tube 24. The castings 38 and 40 form a standard or body on which are mounted the motor 30 and the pumping unit 20, as well as an ignition transformer 44 and a control indicated generally at 46. Annular openings 48 are provided between the fan case 32 and the pumping unit 20 so as to admit air to the fan air intake 50 which opens into the interior of the blower wheel 26.

The pumping unit 20 includes in general an air pump 52, a fuel supply pump 54, a metering pump 56, a pressure regulating valve 58, and a shutoff valve 60.

The air pump 52 (Figs. 2 and 9) may as illustrated be of the rotary sliding vane type and include a rotor 61 secured to the shaft 34 so as to rotate therewith, the rotor 61 being provided with a series of slots, each having a sliding vane 62 therein so that upon rotation of the rotor 61 air

will be drawn through the intake 64 and discharged through the outlet 66. The intake 64 communicates with an air intake chamber 68 which is supplied with air through ports 70 and 72. A duct 74 leading from the outlet 66 conducts the air discharged by the air pump 52 to the interior of the air pipe 76 which delivers such air into the nozzle 22. A pressure regulating valve 78 controls a by-pass port 80 for regulating the discharge pressure of the pump 52.

Oil from a suitable reservoir is supplied to filter chamber 82 through port 84 and through filter 86 to pipe 88 which communicates with conduit 90 leading to the intake 92 of the fuel supply pump 54. This pump 54 is of the gear type and includes gear 94 mounted on shaft 34 to rotate therewith and gear 96 mounted on shaft 98, the teeth of gear 96 being in mesh with those of the gear 94 so as to pump oil through outlet 100 into conduit 102. Conduit 102 delivers the oil discharged by the pump 54 into bearing chamber 104, and conduit 106 conducts oil from bearing chamber 104 into the pressure regulating valve chamber 108. From the valve chamber 108 oil is delivered into the metering pump chamber 110, and from the metering pump chamber 110 oil is delivered through port 112 to the cylinders of the metering pump 56.

The metering pump 56 includes a rotary cylinder member 114 (Fig. 11) provided with aligned pump cylinders 116 and 118, the cylinders 116 and 118 each having a piston 120 reciprocally mounted therein. The pistons each carry a cross pin 122, and a pair of springs 124 confined between the pins 122 biases the pistons 120 away from each other or toward their retracted position in the cylinders. The outer end 130 of each of the pistons bears against a ring 126 which is shiftable off center relative to the shaft 34 so as to determine the stroke of the pistons 120 as well as to effect the delivery strokes thereof. The rotary cylinder member 114 is connected to the shaft 34 so as to rotate therewith, as will herein-after be described, and upon rotation of the cylinder member 114 the outer ends 130 of the pistons will ride around the inner periphery of the ring 126. In order to effect a pumping action by the pistons 120, the ring 126 must be offset relative to the axis of rotation of the cylinder member 114, and hence upon rotation of the cylinder member 114 the pistons 120 will move in and out in their respective cylinders.

The cylinders 116 and 118 are provided with ports 132 and 134, the port 132 registering with the port 112 when one of the pistons 120 is in the position as shown in Fig. 2 at the end of its retractile stroke, while at the same time the port 134 of the other cylinder is in communication with the discharge port 136, the piston 120 in the cylinder 118 at such time being at the end of its discharge stroke.

When the cylinder member 114 is turned 180° from the position illustrated in Figs. 2 and 11, the piston 120 in the cylinder 116 will have completed its discharge stroke and will have discharged oil through port 132 into port 136, while at the same time the other cylinder will be supplied with oil through port 112 and the port 134. The function of the pump 56 is to accurately meter the quantity of oil supplied to the nozzle of the burner.

It will be obvious that by changing the eccentricity of the ring 126 relative to the cylinder member 114, the effective strokes of the pistons 120 may be increased or decreased, depending upon the nature of the adjustment. The position

5 of the ring 126 is determined by a leaf spring 138 confined between the ring 126 and the cylinder block 140, and a ball 142 which bears against a cam surface 144 on an adjusting pin 146. The position of the pin 146 relative to the ball 142 is determined by a spring 148 and a screw 150, the screw 150 being threaded and secured in a threaded hole in the end plate 152 of the pumping unit so that by turning the screw 150 in its hole the pin 146 may be shifted in one direction or the other to react on the ball 142 and thereby to effect the shifting of the ring 126 transversely of the cylinder member 114, the spring 138 biasing the ring 126 downwardly against the ball 142. Springs 141 bias the ring 126 against the inner wall of the chamber 110 so as to permit adjusting movement of the ring 126.

10 The discharge port 134 of the metering pump 56 as shown is connected via duct 154 with the shutoff valve 60. The cylinder member 114 is provided with a plurality of sockets 156 which receive the ends of pins 158 projecting from the rotor 160 of the pressure regulating valve. The face 162 of the cylinder member 114 in which the ports 134 and 132 are provided is a smoothly finished face and seats against a smoothly finished face 164 on the end plate 152. The end of the shaft 34 and the cylinder member 114 are provided with centering sockets in which a ball 166 is disposed so as to center and support the cylinder member 114 relative to the shaft 34.

15 A coil spring 168 surrounding the end of the shaft 34 reacts against the cylinder member 114 to hold the same yieldably against the surface 35 164 of the end plate 152. The other end of the spring 168 reacts against an inwardly directed annular shoulder on a bushing 170 which forms a part of the rotor 160 of the pressure regulating valve 58. The bushing 170 is keyed to the shaft 40 34 so as to rotate therewith by pin 172, and the pins 158 support the rotor 160 on the cylinder member 114. The spring 168 biases the finished face 174 of the rotor 160 against the finished face 176 provided on the left-hand end of the pressure regulating valve chamber 108.

45 From the foregoing it will be clear that the rotor 160 of the pressure regulating valve and the cylinder member 114 of the metering pump are driven by and with the shaft 34 and centered with respect thereto.

50 The pressure regulating valve chamber 108 and the chamber in which the cylinder member 114 rotates are formed by and between the end plate 152 and cylinder block 140. The pressure regulating valve comprises the rotor 160 (Figs. 6 and 55 10) provided with a valve chamber or radially extending passage 182 having a port 184 which communicates with the chamber 108. An inwardly facing valve seat 186 is formed around the port 184 inside of the chamber 182, and a valve 60 in the form of a ball 188 is freely arranged in the chamber 182 and adapted under the influence of centrifugal force to move toward the seat 186 so as to close or tend to close the same and thereby to close or restrict the port 184.

65 The rotor 160 is bored to accommodate the bushing 170 which forms a part of the rotor 160. The chamber 182 extends around the bushing 170 and on the other side thereof where it is provided with a port 190 which is in communication with an annular groove 192 in the face or end wall 176 of the chamber 108. The annular groove 192 is in communication with a duct 194 which forms a part of a return line to the reservoir from which fuel is supplied to the port 84.

70 The gear pump 54 is constructed and arranged

to supply fuel under pressure to the metering pump 56 through conduit 102, bearing chamber 104, conduit 106, valve chamber 108 and port 112, and the pressure regulating valve 58 is disposed in a by-pass between the discharge side of the pump 54 and the intake side thereof, the by-pass being provided by the valve chamber 108, the port 184, the passage 182, the port 190, the groove 192 and the duct 194 which returns fuel to the fuel reservoir for the pump 54, which is the same as returning fuel to the intake side of the pump 54. Actually, if the plug 196 were removed and the port 198 were plugged, the fuel oil which goes through the by-pass just described would be returned directly to the intake side of the gear pump 54 through the pipe 88 and duct 90.

When the shaft 34 is not rotating, the valve member 188 will be unseated from its seat 186 so that at such time the by-pass around the pump 54 is open. When the motor 30 begins to drive the shaft 34, the pump 54 and the rotor 160 will be driven and centrifugal force will urge the ball valve member 188 outwardly toward its seat 186 so as to resist the fluid flow from the discharge to the intake side of the pump 54 inwardly through the port 184, and thereby create a pressure differential.

The outward movement of the valve 188 under the action of centrifugal force will tend to close or restrict the flow of fluid through the port 184. However, pressure will rapidly build up in the chamber 108, and as soon as the pressure in the chamber 108 exceeds the force holding the valve 188 on its seat or urging the same toward its seat, the valve 188 will move inwardly radially and permit the by-passing of fluid back to the inlet side of the pump 54. However, as the speed of the shaft 34 increases, the centrifugal force exerted by the ball valve 188 will increase, such centrifugal force increasing as the square of the angular velocity of the shaft 34, thereby creating a pressure in the valve chamber 108 which corresponds to the square of the speed of rotation of the shaft 34.

The pressure built up in the valve chamber 108 will exist in the duct 106 and the bearing chamber 104, and this pressure is employed to open the valve 60, this pressure when applied to the valve 60 causing the same to open only when a predetermined speed of rotation of the shaft 34 has been attained and permitting the valve 60 to close when the speed of rotation of the shaft 34 drops below a predetermined speed.

The valve 60 is a shut off valve which is arranged in the fuel delivery line between the metering pump 56 and the nozzle 22, the metering pump 56 being arranged to deliver, as previously described, metered quantities of fuel oil through the port 136 and duct 154 to the valve 60, and from thence through the conduit 200 to the oil pipe 202 leading to the interior of the nozzle 22.

The valve 60 is normally closed and is opened by and in response to the pressure in the valve chamber 108, and the valve 60 is constructed and arranged so that it will not open under such pressure until the shaft 34 attains in the neighborhood of 85-90% of its normal running speed. Thus, until the valve 60 is opened, no fuel oil will be delivered to the nozzle 22 by the metering pump 56 even though the same will be operating. The pressure developed by the metering pump 56 prior to the opening of the valve 60 may be relieved by movement of the cylinder member 114 away from the face or wall 164 in which the ports 112 and 136 are provided. How-

ever, as soon as the shaft 34 and the rotor 160 attain sufficient speed, the movement of the valve 188 toward its seat will cause sufficient pressure to develop in the valve chamber 108 to open the valve 60, this pressure being transmitted to the valve 60 through duct 204.

The valve 60 comprises a seat 206 and a valve closure 208 carried by a reciprocal valve member 210. The valve 60 is shown open in Fig. 3. The valve member 210 is slideable in a bore and is connected to a diaphragm 212, one side of the diaphragm being exposed to the fluid under pressure from the duct 204 while the other side of the diaphragm is ported by means of ducts through the hollow valve member 210 and a duct 216 which is in communication with the duct 194. A spring 218 confined in the body of the valve 60 reacts on the diaphragm 212 so as to move the valve member 210 and the valve closure 208 toward the closed position of the valve 60, and the valve 60 will close when the pressure in the duct 204 is dissipated which occurs immediately as soon as the shaft 34 and the rotor 160 fall below a predetermined speed of rotation. In other words, on deceleration of the rotor 160 and shaft 34 from the normal running speed thereof, the ball valve 188 will move to an unobstructing position relative to its seat 186 and the port 184 as soon as the shaft 34 falls below, say for example, 85-90% of its normal running speed. This will dissipate the pressure in the chamber 108 and permit the spring 218 to close the valve 60 by moving the closure 208 to seating position on its seat 206.

The following table computed from the laws governing centrifugal force illustrates the corresponding operating pressures that can be generated at various angular speeds:

Percent of Angular Speed	Percent of Normal Hydraulic Pressure
0	0
10	1
20	4
30	9
40	16
50	25
60	36
70	49
80	64
90	81
100	100

In this instance, resistance to flow is created by directing the rotated mass of the ball valve 188 against the fluid stream flowing into the chamber 182 through the port 184 so as to generate hydraulic pressure in the chamber 108 as a function of the motor speed, the pressure generated being transmitted and directed against the actuating diaphragm 212 of the shutoff valve. Thus the shutoff valve is hydraulically operated and is designed to be opened or closed in response to the changes in pressure developed in the chamber 108 by the pressure regulating valve 58.

Closing of the valve 60 will thus cut off the supply of oil from the metering pump 56 to the nozzle 22 as soon as the motor speed falls below 85-90% of its normal running speed. Of course the valve 60 may be set to shut off the supply of oil at any predetermined pressure or any predetermined speed of the motor.

When the valve 60 is open, metered quantities of oil will be delivered through the conduit 200 to the chamber 220 in the nozzle. Orifices 222 communicating with the chamber 220 supply jets

of oil into passages 224 through which the air supplied by the conduit 74 flows. The metering pump 56 and the air pump 52 are constructed and arranged to supply oil and air at substantially the same low pressure, say for example at a pressure of the order of from 0 to 5 lbs. per square inch. The air flowing through the passages 224 will mix with the oil jets delivered through the orifices 222 to form an emulsion which is delivered through the nozzle opening 226 in the form of a fog into the stream of secondary air flowing in the direction of the arrow through the tube 24, and this mixture is ignited by any suitable ignition means, such for example as that of the spark type employing a pair of electrodes, such as, that shown at 228. The oil fog delivered from the nozzle 22 will expand beyond the end of the tube 24 and burn while in suspension, the fog delivered by the nozzle 22 mixing with the secondary air to form a combustible mixture which will burn cleanly and efficiently.

The shaft 34 is journaled in bearings 230 and 232 which form a part of the pump unit assembly. The pump unit assembly 20 is built up out of a number of machined parts, as shown in various figures, which are suitably secured in assembled relation as illustrated and provided with ducts which conduct the oil and air through the circuits previously described. The actual assembly is shown in Fig. 1, and the sectional views, Figs. 4, 5, 6, 7, 8, 9, 10 and 11, correctly illustrate the construction and shape and size of the various parts. However, in order to illustrate the construction with particular reference to the fluid flow circuits, it was necessary to employ the schematic Figures 2 and 3.

In order to prevent flow of oil along the shaft, a seal indicated generally at 236 is employed, the seal comprising a running seal which prevents the flow of oil leftward along the shaft 34.

In the modification illustrated in Fig. 12 the construction is the same as that previously illustrated except in the following particulars, and to eliminate the necessity of re-describing the construction shown in Fig. 12 the same reference characters will be used as in previous figures to indicate like parts. The principal difference between the construction shown in Fig. 12 and that shown in the other modification resides in the specific construction of the shutoff valve although it operates in the same manner.

In this case the hydraulically operated shutoff valve includes a valve seat 360 shown closed by a valve member 362 in response to the action of spring 364. The duct 154 which conducts oil discharged by the metering pump 56 to the shutoff valve 358 empties into valve chamber 366. Fluid under pressure from the pressure regulating valve chamber 108 is supplied through duct 264 to one side of the diaphragm 212 which bears against the head 213 on one end of a slideable valve member 211, the valve member 211 carrying the valve member 362. Thus when sufficient fluid pressure is applied to the diaphragm 212, the valve member 362 will be unseated and oil from the metering pump 56 and the duct 154 will flow through the ducts in the hollow valve member 211 into the chamber 215 from whence leads the conduit 200 which supplies oil to the nozzle 22.

The suction side of the pump 54 communicates through duct 216 with the chamber on the other side of the diaphragm 212 which is similar to the arrangement shown in the previous modification. A diaphragm 217 separates the discharge cham-

ber 215 of the shutoff valve from the space with which the duct 216 communicates. The sliding valve member 211 has a slight clearance with respect to the bore in which it slides so that when the valve member 362 is unseated, limited quantities of oil may flow past the valve 211 into duct 221 which leads to the chamber 223 of the air pump 52 in which the rotor 61 operates so as to supply minute quantities of oil to the air pump 52 for reciprocating the same and also for improving the pumping efficiency thereof. Such oil as does escape into the air pump 52 will of course be delivered by the pump to the nozzle 22 through the air duct described in connection with the previous modification.

The hydraulically actuated shutoff valve shown in Fig. 12 will function in substantially the same manner as that illustrated in Figs. 1-11, and the operation of the parts shown in Fig. 12 is the same as that shown in Figs. 1-11 except for the differences just described.

While we have illustrated and described preferred embodiments of our invention, it is understood that these are capable of modification and we therefore do not wish to be limited to the precise details set forth but desire to avail ourselves of such changes and alterations as fall within the purview of the following claims.

We claim:

1. An oil burner comprising a liquid fuel pump having an inlet and an outlet, a discharge chamber connected to the outlet of said pump so as to receive liquid fuel discharged by said pump, a rotor in said chamber and arranged to be driven with said pump, said rotor having a valve chamber provided with a port which communicates with said pump discharge chamber, a valve seat within said valve chamber, a centrifugally responsive valve member movable in said valve chamber upon rotation of said rotor toward said valve seat to seat thereon and close said port, a communication between the interior of said valve chamber and the inlet of said pump, a fuel metering pump having its inlet in communication with said discharge chamber so as to be supplied with fuel therefrom, said fuel metering pump being arranged to be driven with said first mentioned pump and rotor, an oil and air mixing nozzle, a connection between said nozzle and the outlet of said fuel metering pump so as to supply fuel from said metering pump to said nozzle, means for supplying air to said nozzle, a pressure operated normally closed valve in said connection, said pressure operated valve including an actuating means therefor hydraulically connected to said discharge chamber and actuated by changes in pressure of the liquid in said discharge chamber above and below a predetermined value for effecting opening and closing movement of said pressure operated valve, said port, valve chamber and communication forming a by-pass between the inlet and outlet of said first mentioned pump, said valve member when seated closing said by-pass, the movement of said valve member towards said seat under the influence of centrifugal force being resisted by the fluid flow through said by-pass from the outlet to the inlet of said first-mentioned pump so as to generate pressure in said discharge chamber as a function of the rotational speed of said rotor.
2. An oil burner comprising a fluid fuel pump having an inlet and an outlet, a discharge chamber connected to the outlet of said pump so as to receive fuel discharged by said pump, a rotor in said chamber and arranged to be driven with

said pump, said rotor having a valve chamber provided with a port which communicates with said pump discharge chamber, a valve seat within said valve chamber, a centrifugally responsive valve member movable in said valve chamber upon rotation of said rotor toward said valve seat to seat thereon and close said port, a communication between the interior of said valve chamber and the inlet of said pump, a fuel metering pump having its inlet in communication with said discharge chamber so as to be supplied with fuel therefrom, said fuel metering pump being arranged to be driven with said first mentioned pump and rotor, a fuel and air mixing nozzle constructed and arranged to mix fuel and air and to discharge a mixture of fuel and air, a connection between said nozzle and the outlet of said fuel metering pump so as to supply fuel from said metering pump to said nozzle, means for supplying air to said nozzle for mixture with the fuel supplied thereto, a pressure operated normally closed valve in said connection, said pressure operated valve including an actuating means therefor hydraulically connected to said discharge chamber and actuated by changes in pressure of the liquid in said discharge chamber above and below a predetermined value for effecting opening and closing movement of said pressure operated valve, said port, valve chamber and communication forming a bypass between the inlet and outlet of said first mentioned pump, said valve member when seated closing said by-pass, the movement of said valve member towards said seat under the influence of centrifugal force being resisted by the fluid flow through said by-pass from the outlet to the inlet of said first-mentioned pump so as to generate pressure in said discharge chamber as a function of the rotational speed of said rotor, and means for flowing a stream of secondary air past said nozzle and into which stream said mixture of fuel and air is discharged.

3. An oil burner comprising an oil pump having an inlet and an outlet, and a by-pass between said inlet and outlet, a centrifugally responsive valve constructed and arranged to resist flow of oil through said by-pass during operation of said pump thereby to create a pressure differential between said inlet and outlet, a fuel metering device having its inlet connected to the outlet of said first mentioned pump so as to be supplied with oil therefrom, an oil and air mixing nozzle connected to said metering device so as to be supplied with oil therefrom, a pressure operated normally closed valve in the connection between said nozzle and said metering device, said pressure operated valve including means connected to said centrifugally responsive valve on opposite sides thereof and operable in response to a predetermined pressure differential created by said centrifugally responsive valve for opening said pressure operated valve, said pump and centrifugally responsive valve being arranged to be actuated simultaneously, means driven with said pump for supplying air to said nozzle for mixture with the oil supplied thereto, and means for supplying a stream of air past said nozzle into which said nozzle discharges a mixture of oil and air.

4. Oil burner construction according to claim 3 wherein said centrifugally responsive valve comprises a rotor having a valve chamber, a port communicating with said valve chamber, a centrifugally responsive valve member arranged in said valve chamber and movable toward said seat

under the influence of centrifugal force, the movement of said valve member toward said seat under the influence of centrifugal force being resisted by the fluid flow through said port, said port forming part of said by-pass.

5. An oil burner comprising an oil pump having an inlet and an outlet, and a by-pass between said inlet and outlet, a centrifugally responsive valve constructed and arranged to resist flow of oil through said by-pass during operation of said pump thereby to create a pressure differential between said inlet and outlet, a fuel metering device having its inlet connected to the outlet of said first mentioned pump so as to be supplied with oil therefrom, an oil and air mixing nozzle connected to said metering device so as to be supplied with oil therefrom, a pressure operated normally closed valve in the connection between said nozzle and said metering device, said pressure operated valve being responsive to and opened by a predetermined pressure differential created by said centrifugally responsive valve, said pump and centrifugally responsive valve being arranged to be actuated simultaneously, means driven with said pump for supplying air to said nozzle for mixture with the oil supplied thereto, and means for supplying a stream of air past said nozzle into which said nozzle discharges a mixture of oil and air, said pressure operated valve including an actuating diaphragm therefor, one side of said diaphragm being connected to said by-pass on the high pressure side of said centrifugally responsive valve and the other side of said diaphragm being connected to said by-pass on the low pressure side of said centrifugally responsive valve.

6. An oil burner comprising an oil pump having an inlet and an outlet, and a by-pass between said inlet and outlet, a centrifugally responsive valve constructed and arranged to resist flow of oil through said by-pass during operation of said pump thereby to create a pressure differential between said inlet and outlet, a fuel metering pump having its inlet connected to the outlet of said first mentioned pump so as to be supplied with oil therefrom, an oil and air mixing nozzle connected to said metering pump so as to be supplied with oil therefrom, a pressure operated normally closed valve in the connection between said nozzle and said metering pump, said pressure operated valve including actuating means therefor hydraulically connected to said by-pass on opposite sides of said centrifugally responsive valve and responsive to a predetermined pressure differential created by said centrifugally responsive valve for opening said pressure operated valve, said pump and centrifugally responsive valve being arranged to be actuated simultaneously, an air compressor driven with said pump for supplying air to said nozzle for mixture with the oil supplied thereto, means for supplying a stream of air past said nozzle into which said nozzle discharges a mixture of oil and air, and means for supplying oil from said metering pump to said air compressor for lubricating the same.

7. An oil burner comprising an oil pump having an inlet and an outlet, a by-pass between said inlet and outlet, a centrifugally responsive valve constructed and arranged to resist flow of oil through said by-pass during operation of said pump thereby to create a pressure differential between said inlet and outlet, a fuel metering device having its inlet connected to the outlet of said first mentioned pump so as to be supplied with oil therefrom, an oil and air mixing nozzle

11

connected to said metering device so as to be supplied with oil therefrom, a pressure operated normally closed valve in the connection between said nozzle and said metering device, said pressure operated valve including actuating means therefor hydraulically connected to said by-pass on opposite sides of said centrifugally responsive valve and responsive to a predetermined pressure differential created by said centrifugally responsive valve for opening said pressure operated valve, means for supplying air to said nozzle for mixture with the oil supplied thereto, means for supplying a stream of air past said nozzle into which said nozzle discharges a mixture of oil and air, and an electric motor operable for actuating said pump, said centrifugally responsive valve and said air supplying means, said centrifugally responsive valve being constructed and arranged so that the pressure differential created thereby is not sufficient to open said pressure operated valve until said motor attains at least 80% of its normal running speed.

8. An oil burner comprising an oil pump having an inlet and an outlet, and a by-pass between said inlet and outlet, a centrifugally responsive rotary valve constructed and arranged to resist flow of oil through said by-pass during operation of said pump thereby to create a pressure differential between said inlet and outlet, a fuel metering device having its inlet connected to the outlet of said first mentioned pump so as to be supplied with oil therefrom, an oil and air mixing nozzle connected to said metering device so as to be supplied with oil therefrom, a pressure operated normally closed valve in the connection between said nozzle and said metering device, said pressure operated valve including actuating means therefor hydraulically connected to said by-pass on opposite sides of said centrifugally responsive valve and responsive to a predetermined pressure differential created by said centrifugally responsive valve for opening said pressure operated valve, means for supplying air to said nozzle for mixture with the oil supplied thereto, and an electric motor operable for driving said pump and rotating said centrifugally responsive valve, the resistance to flow exerted by said centrifugally responsive valve varying in accordance with the square of the speed of rotation of said centrifugally responsive valve.

9. An oil burner according to claim 1 wherein said means for supplying air to said nozzle comprises an air pump arranged to be driven with said liquid fuel pump and wherein means are provided for feeding liquid fuel from said connection to the interior of said air pump for lubricating the same.

10. An oil burner according to claim 1 wherein an electric motor is arranged for driving said pump, said rotor and said air supplying means, said rotor and centrifugally responsive valve member and said pressure operated valve being constructed and arranged so that the pressure in said discharge chamber is not sufficient to open said pressure operated valve until said motor attains approximately 85% of its normal running speed.

11. An oil burner comprising a liquid fuel pump having an inlet and an outlet, a discharge chamber connected to the outlet of said pump so as to receive liquid fuel discharged by said pump, a rotor in said chamber and arranged to be driven with said pump, said rotor having a valve chamber provided with a port which communicates with said pump discharge chamber, a valve seat

5 within said valve chamber, a centrifugally responsive ball valve member movable in said valve chamber upon rotation of said rotor toward said valve seat to seat thereon and close said port, a communication between the interior of said valve chamber and the inlet of said pump, a fuel metering pump having its inlet in communication with said discharge chamber so as to be supplied with fuel therefrom, means for driving said fuel metering pump with said first mentioned pump and rotor, an oil and air mixing nozzle, a connection between said nozzle and the outlet of said fuel metering pump so as to supply fuel from said metering pump to said nozzle, means for supplying air to said nozzle, a normally closed valve in said connection and an actuating means therefor hydraulically connected to said discharge chamber and responsive to a predetermined liquid pressure in said discharge chamber for opening said normally closed valve, said port, valve chamber and communication forming a by-pass between the inlet and outlet of said first mentioned pump, the movement of said valve member towards said seat under the influence of centrifugal force being resisted by the fluid flow through said by-pass from the outlet to the inlet of said pump.

12. An oil burner comprising an oil pump having an inlet and an outlet, and a by-pass between said inlet and outlet, a centrifugally responsive valve including a centrifugally responsive valve member constructed and arranged to resist flow of oil through said by-pass during operation of said pump thereby to create a pressure differential between said inlet and outlet, a fuel metering device having its inlet connected to the outlet of said first mentioned pump so as to be supplied with oil therefrom, an oil and air nozzle connected to said metering device so as to be supplied with oil therefrom, a normally closed valve in the connection between said nozzle and said metering device, said normally closed valve including actuating means therefor hydraulically connected to said by-pass on opposite sides of said centrifugally responsive valve and responsive to a predetermined pressure differential created by said centrifugally responsive valve for opening said normally closed valve, said pump and centrifugally responsive valve being arranged to be actuated simultaneously, means driven with said pump for supplying air to said nozzle, and means for supplying a stream of air past said nozzle into which said nozzle discharges a mixture of oil and air.

13. An oil burner according to claim 12 wherein an electric motor is arranged for driving said pump, and said centrifugally responsive valve, said centrifugally responsive valve and said normally closed valve being constructed and arranged so that said pressure differential is not sufficient to cause the opening of said normally closed valve until said motor attains at least 80% of its normal running speed.

14. An oil burner comprising an oil pump having an inlet, an outlet, and a by-pass between said inlet and outlet, a centrifugally responsive valve constructed and arranged to resist flow of oil through said by-pass during pump operation thereby to create a pressure differential between said inlet and outlet, an oil and air mixing nozzle connected to said pump so as to be supplied with oil therefrom, a pressure operated normally closed valve in the connection between said nozzle and said pump, said pressure operated valve being hydraulically connected to said by-

pass on opposite sides of said centrifugally responsive valve so as to be responsive to and opened by a predetermined pressure differential created by said centrifugally responsive valve, said pump and centrifugally responsive valve being arranged to be actuated simultaneously, means driven with said pump for supplying air under pressure to said nozzle for mixture with the oil supplied thereto, said nozzle being constructed so as to mix the oil and air supplied thereto and to discharge a mixture of finely divided oil particles and air, means for metering the rate at which oil is supplied to said nozzle from said pump, and means for supplying a stream of secondary air past said nozzle into which said mixture of oil and air is discharged.

15. Oil burner construction according to claim 14 wherein said metering means is disposed in the connection between said pressure operated valve and said oil pump.

16. An oil burner comprising an oil pump having an inlet, an outlet, and a by-pass between said inlet and outlet, resistance means in said by-pass operative to resist the flow of oil therethrough thereby to create a pressure differential between said inlet and outlet, a nozzle connected to said pump so as to be supplied with oil therefrom, means operative for supplying air under pressure to said nozzle for mixture with the oil supplied thereto so that said nozzle operates to discharge a spray of a mixture of finely divided oil particles and air, a pressure operated, normally closed valve in the connection between said nozzle and said pump, said pressure operated valve being hydraulically connected to said by-pass on opposite sides of said resistance means so as to be responsive to and opened by a predetermined pressure differential created by said resistance means, means for metering the rate at which oil is supplied to said nozzle from said

pump, and means for supplying a stream of secondary air past said nozzle into which said spray of oil particles and air is discharged.

17. An oil burner comprising an oil pump having an inlet, an outlet, and a by-pass between said inlet and outlet, resistance means in said by-pass operative to resist the flow of oil therethrough thereby to create a pressure differential between said inlet and outlet, a nozzle connected to said pump so as to be supplied with oil therefrom, means operative for supplying air under pressure to said nozzle for mixture with the oil supplied thereto so that said nozzle operates to discharge a spray of a mixture of finely divided oil particles and air, a normally closed valve in the connection between said nozzle and said pump, means hydraulically connecting said valve to said by-pass and operable for effecting opening of said valve when said resistance means creates a predetermined pressure differential, means for metering the rate at which oil is supplied to said nozzle from said pump, and means driven with said pump for supplying a stream of secondary air past said nozzle and into which said spray of oil particles and air is discharged.
